OIL WELL CASING PUMP

Hubert D. Collins, Tulsa, Okla., assignor to Lam-tex Equipment Corporation, Fort Worth, Tex., a corporation of Texas.

Application December 4, 1942, Serial No. 467,846

10 Claims. (Cl. 103—221)

This invention relates to new and useful improvements in pumping mechanisms for flowing oil wells and the like. It deals particularly with well pumps of the type known as casing pumps, which are located and sealed in place inside of the usual well casing and make use of the casing for conducting oil to the ground surface.

Oil well casing pumps as heretofore constructed are sealed in pumping position by forcing a frusto-conical mandrel on the pump head into an expansible annular packer so as to pack the top of the packer against the surrounding well casing. When it is desired to remove the pump or pump head, it is first necessary to lift the mandrel out of the packer so that the seal between the top of the packer and the well casing may be broken. The column of oil lying above the pump, however, still bears on the packer and hinders movement of the pump assembly. For relief from this condition, drainage ports have heretofore been provided in a drain sleeve just below the packer, so that oil may pass between the packer and a drain tube that depends from the mandrel, and then through these drainage ports. Also, circular rows of drainage holes have been provided in the lower end of the drain tube and in the drain sleeve, respectively, so as to register and allow drainage when the mandrel is lifted from the packer and to be sealed off from each other by an intermediate packing when the mandrel is seated in the packer.

Notwithstanding the provision of such structures, trouble frequently is encountered in removing the usual casing pump from a well hole. Also, the resilient packer is likely to drag against the casing and be damaged both when removing the pump and when running it into the hole. A metal packer shoe sometimes is attached to the lower side of the packer to protect it against damage during the lowering of the pump into the well. A further source of trouble is that the drainage ports just below the packer sometimes become clogged by shale, sand or other solid matter passing and lodging between the packer and the drain tube when the mandrel is unseated. Moreover, the usual casing pump is comparatively large and requires extra material and machine work for its manufacture, as compared with casing pumps embodying the features of my present invention.

One of the objects of this invention is to provide a new and improved casing pump construction which facilitates the removal of the pump from a well after pumping operations.

Another object is to provide such a construc-

tion which reduces the likelihood of damage to the packer during movements of the pump in a well casing.

Another object of this invention is to provide a casing pump construction which enables free drainage of liquid past the packer when the mandrel is unseated, and which prevents solid matter from entering and lodging in the space between the drain tube and the packer.

10 Another object is to provide a casing pump construction which eliminates the usual radial drainage holes in the drain sleeve below the packer yet overcomes the difficulties which it is the purpose of such structure to avoid.

15 Another object of this invention is to provide a casing pump construction which is smaller in length and less costly to manufacture than known oil well casing pumps.

20 The foregoing and other features and advantages of my invention will become apparent from the following description of an illustrative embodiment thereof, when considered in connection with the accompanying drawing, in which,

Figure 1 and Figure 1a are longitudinal views, 25 partly in cross section, showing, respectively, upper and lower portions of the illustrative pump mechanism;

Figure 2 is a fragmentary elevation of part of the drain sleeve and drain tube assembly;

30 Figure 3 is a transverse cross section substantially along line 3—3 of Figure 1; and

Figure 4 is an enlarged longitudinal cross section showing the mechanism of Figure 1 with the packer sealed against the well casing.

35 Figures 1 and 1a show the relationship of the pump parts as located in a well casing 10 with the mandrel 12 unseated; and Figure 4 shows the parts of Figure 1 disposed in pumping condition, with the mandrel 12 seated in and sealing the packer 14 against the surrounding casing. A pump rod 16 forms part of the usual string of sucker rods (not shown) by which to lower or raise the pump in the well and to reciprocate the

40 pump piston or sucker 18 (Figure 1a) when the pump is located and sealed in pumping position. The piston 18 operates in a working barrel 20 and carries a travelling valve 22 and sealing rings or gaskets 24. A valve housing 26, secured to

45 the lower end of the working barrel, encloses a standing valve 28 through which oil is admitted from the well formation into the working barrel on the upward stroke of piston 18. The pump assembly may be supported at pumping position

50 in any known manner, such as by a suitable an-

choring device (not shown) attached thereto below the working barrel.

The working barrel 20 is connected with the packer 14 through tubular means including a drain sleeve 30 and one or more coupling sleeves or adaptors 32. The packer itself is made of an oil-resistant synthetic rubber, such as "Neoprene," or of other suitable rubber-like material, and is constructed in a novel manner as hereinafter described. The packer is permanently molded and bonded to a bushing 15, by which it is firmly secured to the upper end 31 of the drain sleeve 30.

A drain tube 40 fits inside of the drain sleeve 30 and is movable axially with respect thereto to a limited extent determined by the length of an axial slot 42 in the drain sleeve and the size of a lug 44 that is fixed to the drain tube for sliding movement in slot 42. The slot has a horizontal leg 43 at its top to receive the lug and thus hold the drain tube assembly against substantial axial movement during the raising or lowering of the pump in a well. The drain tube 40 depends from a pump head 50, to which it is directly attached. Pump rod 16 extends vertically through the drain tube 40 and pump head 50. The lower part of the pump head constitutes the mandrel 12, being frusto-conical in shape so as to fit into and expand the packer 14. The head 50 is hollow and has lateral openings 52 therein so that oil may pass upwardly from the working barrel through the drain tube and pump head and thence into the casing 10 above the packer.

According to the present invention, the expandable packer 14 is formed and constructed to have a minimum diameter adjacent its top portion, so that its inherent resiliency will strip it away from the casing 10 when the mandrel 12 is unseated, and preferably also so that it fits closely against the drain tube 40 in its normal unexpanded condition. As illustrated in Figure 1, the outer surface of the packer is made to curve or taper inwardly from its middle portion 14a to the top portion 14b, so that the "pack-off" or sealing effected by forcing the mandrel thereinto occurs adjacent the middle portion of the packer, substantially as shown in Figure 4, instead of at the top only as in prior casing pump constructions. Also, the inner surface of the packer preferably is made to curve or taper inwardly to a slight extent from the bottom almost to the top portion thereof, which further ensures self-induced inward movement of the packer into sealing engagement with the drain tube 20 when the mandrel is unseated. In other words, the average diameter of the packer preferably decreases progressively from the bottom substantially to the top portion thereof. At the top of the packer, as shown at 14c, the inner surface preferably curves outwardly to facilitate seating of the mandrel and cause the "pack-off" zone to extend to the middle portion 14a.

With the packer so constructed, the packer strips itself away from the well casing 10 and provides the maximum available space between its outer side and the casing whenever the mandrel is unseated, so that the drainage of liquid past the packer is materially improved. The same construction alleviates the danger of damaging the packer during the lowering or the raising of the pump in a well, thus making it unnecessary to attach special metal packer shoes under certain conditions. Also, the drainage ports usually provided in the drain sleeve just below the packer may be eliminated, leaving the drain sleeve imperforate at that location; and since

the packer moves into sealing engagement with the drain tube 40 as the mandrel is unseated, liquid and suspended solid matter are prevented from entering and lodging in the space between the body of the packer and the drain tube (see Figure 1). A further feature of this construction is that the packer may be made shorter than heretofore without lessening its sealing effect or its resistance to hydrostatic pressures.

- 10 To permit drainage of oil through the pump head and drain tube when removing the pump from a well, radial drainage ports 41 are provided near the lower end of the drain tube 40, and the slot 42 which receives lug 44 is cut entirely through the drain sleeve and connected with an inwardly facing annular groove 45 in the drain sleeve so that the drainage ports 41 will communicate with and drain through the groove 45 and slot 42 when the mandrel is lifted, as shown in Figures 1 and 3. A suitable packing ring 54, such as a chevron packing, is disposed between the lower end of the drain sleeve 30 and the drain tube 40 to permit relative sliding movement of the drain tube yet form a leak-proof seal when the parts are in pumping condition, as in Figure 4. This single packing ring suffices. The arrangement of the slots 42 for registration with the ports 41 and the provisions for full drainage outside the packer instead of through other drainage facilities in the drain sleeve make it practicable to employ a packer and drain sleeve assembly that is substantially smaller and less costly to manufacture than in the case of oil well casing pumps heretofore used.
- 25 35 While I have shown and described details of an illustrative embodiment of my invention, it will be understood that various alterations may be made in its practical embodiments without departing from the substance of this disclosure, 40 as intended to be set forth in the appended claims.

I claim:

1. An expandable packer for an oil well casing pump, adapted to be packed by a tapered mandrel into sealing contact with a surrounding well casing, comprising an annular body of elastic material having its outer surface tapering inwardly from its middle portion to its top so as to be packed by the mandrel adjacent its middle portion and to strip itself away from the casing when the mandrel is withdrawn.

2. In an oil well casing pump comprising a pump barrel, a drain sleeve connected with the top of the pump barrel to facilitate removal of the pump from a well casing, a drain tube extending into the sleeve and slidably relative thereto, a mandrel at the top of the drain tube and an annular expandable packer secured to the top of the drain sleeve to be packed by the mandrel into sealing contact with a surrounding well casing, a packer having its outer surface tapering inwardly from its middle portion to its top portion and having its inner surface tapering inwardly from its bottom substantially to its top portion, such that the packer fits closely against and forms a seal with the drain tube when the mandrel is withdrawn.
3. An expandable packer for an oil well casing pump, adapted to be packed by a conical mandrel into sealing contact with a surrounding well casing, comprising an annular body of elastic material having a "pack-off" section adjacent its middle portion to make such sealing contact and having a progressively decreasing average diameter from the middle portion substantially to the top portion thereof.

4. An expansible packer for an oil well casing pump, adapted to be packed by a mandrel into sealing contact with a surrounding well casing, comprising an annular rubber-like body the outer surface of which is substantially vertical from its bottom to its middle portion and tapers inwardly from the latter to its top portion, and the inner surface of which tapers inwardly from its bottom substantially to its top portion.

5. In an oil well casing pump comprising a pump barrel, a drain sleeve connected with the top of the pump barrel to facilitate removal of the pump from a well casing, an inner drain tube extending into the sleeve and slidable relative thereto, a mandrel at the top of the drain tube and an annular expansible packer of rubber-like composition secured to the top of the drain sleeve, a packer formed to be packed by the mandrel adjacent its middle portion to seal the pump in a well casing and having its minimum diameter adjacent its top portion whereby to strip itself from the well casing and form a seal with the drain tube when the mandrel is withdrawn therefrom.

6. In an oil well casing pump comprising a pump barrel, a drain sleeve connected with the top of the pump barrel to facilitate removal of the pump from a well casing, a drain tube extending into the sleeve and slidable relative thereto, a mandrel at the top of the drain tube and an annular expansible packer secured to the top of the drain sleeve, a drain sleeve which is imperforate adjacent the packer and a packer formed with means for stripping itself away from a well casing and for holding itself in sealing contact with the drain tube when the mandrel is withdrawn from the packer.

7. In an oil well casing pump comprising a pump barrel, a drain sleeve connected with the top of the pump barrel to facilitate removal of the pump from a well casing, a drain tube extending into the sleeve and slidable with respect thereto, a mandrel at the top of the drain tube and an annular expansible packer secured to the top of the drain sleeve to be packed by the mandrel into sealing contact with a surrounding well casing, interfitting lug and slot means respectively on the drain tube and in the drain sleeve to limit relative axial movement thereof, a slide packing inside the drain sleeve below said slot means to seal the drain sleeve to the drain tube when the mandrel is seated in the packer, said slot means opening through the wall of said drain sleeve, and drainage means opening through said drain tube near the lower end thereof and

disposed to register with said slot means when the mandrel is withdrawn from the packer whereby to drain oil from above the pump in a well casing.

5 8. In an oil well casing pump comprising a pump barrel, a drain sleeve connected with the top of the pump barrel to facilitate removal of the pump from a well casing, a drain tube extending into the sleeve and slidable with respect thereto, a mandrel at the top of the drain tube and an annular expansible packer secured to the top of the drain sleeve to be packed by the mandrel into sealing contact with a surrounding well casing, interfitting lug and slot means on the drain tube and in the drain sleeve, respectively, to limit relative axial movement thereof, said slot means opening through the wall of the drain sleeve, drainage means opening through the drain tube and disposed to communicate with said slot means when the mandrel is withdrawn from the packer, packing means between the drain sleeve and drain tube for sealing off said drainage means from said slot means when the mandrel is seated in the packer, said drain sleeve being imperforate above said slot means and said packer being formed to strip itself away from the well casing and fit closely against the drain tube when the mandrel is withdrawn from the packer whereupon to provide free passage of liquid between the packer and the well casing and simultaneous flow of liquid from the drain tube through said drainage means and said slot means.

9. A packer unit for an oil well casing pump or the like comprising a cylindrical bushing threaded for connection to the upper end of a tubular pump element and an annular expansible packer of rubber-like material molded and bonded to said bushing, said packer having its average diameter progressively decreasing from the bottom substantially to the top portion thereof.

10. In a casing pump for oil wells or the like comprising a cylindrical drain sleeve adapted to be connected with a pump barrel and to carry an expansible packer at its upper end, a cylindrical bushing threadedly connected to the upper end of the drain sleeve and an annular expansible packer of rubber-like material molded and bonded to said bushing, said packer having its average diameter progressively decreasing from the bottom substantially to the top portion thereof, said drain sleeve having an inverted L-shaped slot cut through its wall and being otherwise substantially imperforate.

HUBERT D. COLLINS.
